[57] CLAIM

The ornamental design for an organ, substantially as shown and described.

DESCRIPTION

FIG. 1 is a front, top and left side perspective view of the organ showing my new design.

FIG. 2 is a front elevational view; and

FIG. 3 is a right side elevational view.

The back of the music desk is plain and unornamented. The fabric covering the lower front board and sides is continuous throughout the boundaries thereof. The left side of the organ is a mirror image of the right side as shown.

FIG. 3
